UNITED STATES PATENT OFFICE.

DAVID E. DUNKLE, OF NORWICH, PENNSYLVANIA.

TYPE-WRITER ATTACHMENT.

1,256,447.

Specification of Letters Patent. Patented Feb. 12, 1918.

Application filed April 28, 1916. Serial No. 94,214.

To all whom it may concern:

Be it known that I, DAVID E. DUNKLE, a citizen of the United States, residing at Norwich, in the county of McKean and State 5 of Pennsylvania, have invented new and useful Improvements in Type-Writer Attachments, of which the following is a specification.

The invention relates to a typewriter attachment, and more particularly to the class 10 of electrically operated carriage shifters for typewriters.

The primary object of the invention is the provision of an attachment of this character 15 wherein the platen carriage of the typewriter, after being moved to the left on operating the keys, will be automatically moved to the right, thereby obviating the hand shifting of the carriage, as usual, 20 which is laborious to the typist when operating the typewriter machine.

Another object of the invention is the provision of a typewriter attachment of this character wherein the carriage is moved in 25 both directions when operating the keys of the typewriter machine, one of the keys being designed to close a normally open electric circuit which has arranged therein a solenoid and its core of novel construction 30 to assure the moving of the carriage the entire distance to the right with despatch, yet the said carriage can be moved in this direction by hand as usual.

A further object of the invention is the 35 provision of an attachment of this character wherein on the automatic travel of the carriage to the right the platen thereon will be turned or rotated for the feed of said platen in advancing the paper one or more lines 40 for the proper line spacing of typewritten matter as may be required, thereby obviating the hand manipulation of the platen for the line spacing of the typewritten matter.

A still further object of the invention is 45 the provision of a typewriter attachment of this character wherein the construction thereof permits the same to be applied to different types of standard makes of typewriter machines without requiring any material alteration or changes therein and thus 50 permitting the automatic shifting of the carriage from left to right and the turning of the platen for the spacing of the typewritten matter upon the sheet when the 55 typewriter machine is operated.

A still further object of the invention is

the provision of an attachment of this character which is simple in construction, reliable, efficient and positive in operation, strong, durable and inexpensive in manufacture and installation.

Other objects will be in part obvious and in part hereinafter pointed out.

The invention accordingly consists in the features of construction, combination of elements and arrangement of parts which will be exemplified in the construction hereinafter described, and the scope of the application of which will be indicated in the appended claim.

In the accompanying drawings:

Figure 1 is a top plan view of a typewriter machine showing the attachment constructed in accordance with the invention applied;

Fig. 2 is an end elevation thereof.

Fig. 3 is an enlarged longitudinal horizontal sectional view through the solenoid employed.

Fig. 4 is a fragmentary vertical transverse sectional view showing in detail the circuit closing switch key.

Fig. 5 is a horizontal sectional view through the switch key.

Fig. 6 is a detail perspective view of one 85 of the brackets for fastening the attachment to the typewriter.

Similar reference characters indicate corresponding parts throughout the several views of the drawings.

Referring to the drawings in detail, A designates generally the frame of a typewriter, which is of the ordinary well known construction, B the movable carriage and C the rotatable platen which is journaled in 95 the carriage for movement therewith, the said platen being rotated in a step by step manner for the line spacing of the typewritten matter through the medium of the hand operated ratchet mechanism D which, 100 as usual, is at the right hand end of the machine.

It is of course understood that the movable carriage is operated through the usual ratchet and escape mechanism from right to 105 left on operating the keys E of the typewriter machine for the letter and word spacing of the typewritten matter.

The shifter attachment comprises an electrically magnetized or energized solenoid 110 including a cylindrical casing 10 preferably made from hard rubber and having at op-

posite ends removable heads or caps 11, while interiorly of this casing is arranged the wiring 12 which is coiled or convoluted and forms the magnetic field of the solenoid, 5 which wiring is concentric with a central guide sleeve 13 preferably made from wood fiber and in which travels a magnetic core of the solenoid, the sleeve 13 being enlarged for a portion of the inner end thereof to receive a glass insulator tube 15, in which latter and the sleeve 13 works the core 14 when the solenoid is magnetized, and this solenoid is arranged within a normally open electric circuit including the current wires 10 16 and 17 and a battery 18 which is suitably held, although the said wires can be connected with an electric main having arranged in series therewith a rheostat or current reducer of any suitable form, one of the 15 current wires being broken for the interposing of a circuit closer or switch herein-after fully described. The solenoid is fastened upon the frame A of the typewriter machine, and for this particular purpose 20 there is provided a pair of brackets 19 which are secured to the heads of the caps 11 and are fastened to the hangers 20 supporting the track for the movable carriage B of the typewriter machine. Secured to 25 the movable carriage B at the rear thereof in any suitable manner is an elbow shaped arm 21 which has its short branch 22 insulated from and connected to the core 14 so that on movement of the said core inwardly 30 of the solenoid by the magnetizing thereof the carriage B will be shifted from left to right.

The circuit closer switch comprises a base 23 formed with a vertical housing 24, in the 35 lower end of which is fitted a combined binding and contact post 25 to which is connected one stretch of the broken circuit wire, while slidable in the housing 24 is a spring held plunger 26 to which is connected the 40 other stretch of the broken circuit wire and on the outer end of this plunger is formed a head 27 provided with a key. When the plunger 26 is moved inwardly in the housing 24 to engage with the contact 25 the electric 45 circuit is closed so that the solenoid will become energized for attracting the core 14 to pull the same inwardly within the solenoid and thus move the carriage B from left to right, thereby shifting the same automatically. When pressure is relieved from the plunger 26 this spring will normally 50 retract the same from the contact 25, thereby opening or breaking the electric circuit, so that the carriage B will be free for step by step movement from right to left on operating the keys E of the typewriter machine. Formed on the right hand end head or cap 11 centrally thereof is an air cylinder 28 having an air inlet port 29 in its outer end provided with a valve seat 30 in which is ar-

ranged a ball valve 31, the latter being held within an adjustable screw plug 32 which is threaded in the port 29 and is formed with an air intake aperture 33 having at the inner end thereof a valve seat 34 so that 50 the ball valve 31 will alternately engage the respective seats 30 and 34 for permitting the intake and exhaust of air to and from the cylinder 28, while slidably within the said cylinder 28 is an air cushion plunger 75 25 which is adapted to be attracted by the solenoid for the drawing of the same inwardly of the cylinder 28, thereby sucking air through the plug 32 into the said cylinder and on pulling inwardly upon the core 80 14 the said plunger 35 is acted upon thereby and its impact against the air confined within the cylinder 28 will serve as a cushion for the core, thereby avoiding the pounding of the core within the solenoid and also 85 gradually retarding the movement thereof when drawn fully within the solenoid. The plug 32 is readily adjustable and is held in such adjusted position through the medium of a lock nut 36 threaded thereon and working against the outer end of the cylinder 28 so that the movement of the valve may be limited as the occasion may require to vary the action of the air cushion plunger 90 35 interiorly of the said cylinder. 95

In lieu of the ordinary end plate at the left hand end of the movable carriage B is substituted a plate 37 which has journaled therein a horizontally disposed rocking pintle 38, on the outer end of which is fixed 100 a trip lever including the sections 39 and 40, respectively, which are pivotally connected to each other at 41, the section 40 being free for swinging movement in one direction but limited in its swinging movement in the 105 opposite direction so that on movement of the carriage to the left the said lever will freely pass over a stationary trip 42 mounted on the top of the frame A of the typewriter, but on movement of the carriage to 110 the right the trip lever will be actuated by the trip 42 for a purpose presently described. Fixed to the pintle 38 is a hub 43 formed with a nose 44 engaging a slide pin 45 held in a guide 46 of the plate 37, the pin 115 45 being designed to act upon a rocking bell crank lever 47 which is pivoted to the plate 37 and is normally held against rocking movement by means of a spring 48 acting thereon, and to this lever is pivoted a ratchet 120 feed dog 49 which is adapted to engage a ratchet wheel 50 fixed to the platen at the left hand end thereof so that on actuation of the trip lever, including the sections 39 and 40, when the carriage moves from left 125 to right the ratchet dog 49 will engage the ratchet wheel 50 for automatically turning the platen C for the feeding of the paper thereby to line space the typewritten matter thereon. It will be apparent that this auto- 130

matic feed of the platen for the line spacing of the typewritten matter is independent of the hand operated ratchet feed mechanism for the said platen of the ordinary well known construction.

It will be apparent that when the carriage has been moved from right to left and the electric circuit is closed the solenoid attracts the core 14, thereby automatically shifting the carriage from left to right, and on this movement of the carriage the trip lever will become automatically actuated by the trip 10 42 for rotating the platen C for the line spacing of the typewritten matter, it being understood of course that the dog 49 can be manually set to vary the automatic line spacing in a manner similar to the setting of the feed dog of the hand operated ratchet mechanism for rotating the platen, as usual.

From the foregoing description, taken in connection with the accompanying drawings, the construction and manner of opera-

tion of my improved spacing mechanism will be readily apparent and, therefore, a more extended explanation has been omitted. 25

Having thus described my invention, I claim:

The combination with a solenoid, a core within said solenoid, a normally open circuit having the solenoid arranged therein, 30 a circuit closer arranged in said circuit, an air cylinder formed at one end of the solenoid and having an air port provided with a valve seat, an adjustable plug arranged in the air port and having an air intake 35 aperture, and a spherical valve located within the port in the cylinder and working against the seat in said port and the plug.

In testimony whereof I affix my signature in presence of two witnesses.

DAVID E. DUNKLE.
